UNITED STATES PATENT OFFICE.

EDWIN M. KELLOGG, OF CHICAGO, ILLINOIS.

GRAIN-BINDER.

SPECIFICATION forming part of Letters Patent No. 485,157, dated October 25, 1892.

Application filed February 26, 1886. Serial No. 193,833. (No model.)

To all whom it may concern:

Be it known that I, EDWIN M. KELLOGG, a citizen of the United States, residing at Chicago, in the county of Cook and State of Illinois, have invented certain new and useful Improvements in Grain-Binders, of which the following is a specification.

In the past few years a novel form of holder has been introduced and become known under 10 the term "crown-disk holder." Such a holder I have described in Letters Patent granted me on the 23d day of March 1886, No. 338,417, and have therein claimed certain combinations into which it enters or by which it is actuated. 15 This holder consists of a disk with an upturned notched flange saddled by a shoe and has heretofore been mounted upon a spindle parallel with the tyer-spindle, so that the cord is carried toward the knotter in a plane at 20 right angles to the tyer-spindle. Such arrangement requires, also, that the cord-strands shall be laid by the binder-arm in the notch nearest the tying-bill and close to the shoe which saddles the flange; but in practice, 25 owing to the position of the holder-spindle relatively to the tyer-spindle, it has been proven that there is great liability of the binder-arm laying the strand last brought up into both that notch and the notch opposite, so 30 that when the holder-disk begins a revolution the strand will be pulled aside close to the eye of the binder-arm and may be sprung out of the notch that is just entering the shoe, so as not to be grasped or not firmly grasped. 35 To remedy this and to provide for lifting the cord in its lateral travel toward the knotter-jaws so as to be properly laid and caught between the latter, I incline the holder-spindle so as to raise the side of the holder-disk nearest 40 the tying-bill and depress the side farthest therefrom relatively to the plane of revolution of the tying-jaws, thus insuring that the cord-strands laid by the binder-arm, while they fall into the notch in advance of the shoe, 45 cannot by any possibility reach the opposite notch and that they shall properly engage the tyer and be directed between its jaws as it nears the end of the revolution. Novel means are also adopted to actuate the holder. 50 Another difficulty experienced in this class of binders is that the strand, being placed about the gavel by the binder-arm, occasion-

ally becomes entangled in the grain and is pushed to one side, so that it does not properly reach the knotter, or so that the binder-arm slips past it in the cord-slot and then bars its proper approach to said knotter. This has usually been provided for by the employment of a tucke either upon the binder-arm or else above the breast-plate and operated by an irregular flange or groove upon the tyer-cam, involving extra mechanism and extra weight. It being an object to place a minimum of labor on the tyer-cam and to reduce the weight and number of parts as much as possible, those 65 just enumerated are dispensed with and a shoulder or rounded breast is formed upon the binder-arm at such a point and of such easy outline that while readily piercing the inflowing stream of grain it will by sweeping 70 curved reaches of the grain-depressing ribs depending from the breast-plate on each side of the cord-slot practically close the cord-slot on the side adjacent to the grain without passing therethrough, thus pushing the strand before it as the binder-arm carries it around the gavel and bringing it up close to the tying-bill. 75

Various other improvements are set forth in the ensuing description and pointed out in 80 the claims.

In the drawings, Figure 1 is a vertical sectional elevation of so much of a binding attachment embodying my invention as is necessary to an understanding thereof. Fig. 2 85 is a plan view from above, showing breast-plate, knotter, and holder with their spindles in section and the tyer shaft and cam removed; Fig. 3, an elevation in section on the correspondingly-numbered line in the first 90 figure, looking from the grain side; Fig. 4, an under side detail of the outer or lower end of the breast-plate; Fig. 5, a section through the cam on the line 5 of Fig. 1; Fig. 6, a vertical section through the holder and its spin- 95 dle-bearings; Fig. 7, a section through breast-plate and binder-arm, as indicated by like numerals in first figure, looking from the stubble side; Fig. 8, an enlarged detail of the crown-disk and its shoe; Fig. 9, a detail of 100 the knotter-pinion and its shoes; Figs. 10, 11, and 12, diagrammatic projections of the tyer-cam and knotter to explain the method in which the latter is actuated; and Figs. 13, 14,

and 15, views in rear and stubble side elevation and in section of a modification of the invention for the purpose of actuating the holder.

5 A represents the decking of a binding attachment or that part which forms the flooring of the grain-chute, and B is the binder-arm mounted upon a rock-shaft therebeneath and provided with the usual concentric guard-finger. Above this decking and forming the top of the grain-passage or packing-chamber is the breast-plate C, also slotted for the play of the binder-arm and having ribs c alongside each under edge of said slot to keep the 15 waist of the gavel from contact with the plate, and above the breast-plate is the main tyer-shaft D, supported, as usual, in an overhung arm from the post-frame. A bracket D', sleeved upon this tyer-shaft and braced by a 20 stay-rod d, leading to support on the harvester-frame, depends from said shaft and has its feet bolted to and supporting the breast-plate. A bearing d', formed in this bracket, receives the spindle of the knotter or 25 tying-bill E, which, as usual, is formed with a rigid jaw e and a pivoted jaw e', the latter being controlled by means of a spring-cam e², which acts upon the outer side of its heel extension to close it, and a fixed cam e³ upon 30 the stock or bracket, which acts upon the inner side of said heel extension to temporarily open it in order to receive the crossed ends of the band, the action of the spring-cam immediately succeeding to close the jaws, grasping 35 these ends and holding them while the loop is drawn over them.

At the upper end of the tyer-spindle is secured a bevel-pinion F, having upon its hub two delay-shoes f and f' in different planes 40 transverse of the spindle and at an obtuse angle to each other, the lower shoe being intended to hold the knotter at rest during the long interval preceding the next binding operation, and the upper shoe having for its object to lock it temporarily in position while 45 the bundle is being ejected before it reaches its original or starting point. The teeth of the pinion are cut away from the initial end of the upper shoe to near its rear end, forming 50 a gap f², one wall of which is about flush with said shoe, and the other wall of which is formed by a tooth of the pinion near said rear end, all for a purpose that will presently appear.

55 Upon the tyer-shaft is mounted the tyer-cam G, consisting of a wheel or disk provided on the face adjacent to the tyer-spindle with a segment-rack g, not having, as usual, sufficient teeth to give the tyer a complete turn, 60 but less than that number, so that as the tyer-pinion passes off of the rack the jaws of the knotter will stop in a position trending outwardly along the slot in the breast-plate or in the general direction of said slot. Beyond 65 this rack, to engage with the upper shoe of the pinion, is a delay-ledge g', of such length as to allow the ejector-fingers G', which come

in contact with the gavel at the moment the shoe rides upon the initial end of the ledge, to complete their action just as it reaches the 70 farther end. At this latter point is located a solitary tooth g², which, entering and passing along the gap in the pinion, engages with the rear wall or gear-tooth and revolves said pinion just sufficient to bring the knotting-jaws 75 to a position completing their revolution or their original or starting position, pointing right across the line of the slot in the breast-plate, when the second delay-shoe on the pinion falls upon a succeeding delay-ledge g³, described on a greater radius than the first, to prevent interference, by which the knotter is 80 locked in position until its pinion engages with the segment in the next tying operation. That portion of the slot H in the breast-plate 85 through which the binder-arm plays is straight, as usual, but adjacent to the knotter it becomes oblique, trending toward the knotter-spindle, or, rather, forming a finger h, projecting from the side farthest from the spindle 90 into a recess or cut-away portion beneath said spindle and terminating opposite or almost opposite to its axis, at which point the slot returns slightly inward for a space beneath and about parallel with the knotter-jaws in their 95 transverse position, then curves gradually outward and obliquely away from the knotter in the direction of the trend of its jaws, when their pinion runs off its segment and the first shoe engages with its ledge. Thus when 100 the knotter is stopped at the conclusion of the binding operation, with its jaws directly across the general line of the slot, the cord-strands as they are laid, first by the recession of the binder-arm and then by its approach, will be deflected along the upper or inner edge of the finger and laid on the chin of the knotter close to its spindle and retained there, whether they escape past the 105 end of the finger or remain upon it to be carried thereover and into the lower returning reach of the slot by the revolution of the knotter. The slight inward or return curve of the slot prevents any tendency of the 110 strands to slip along toward the nose of the 115 knotter should they escape from the finger, and in any event the knotter-jaws in their transverse position so completely close the slot that the strands are absolutely barred from passage until they have been tied, while 120 the oblique continuation of said slot allows the band to be pulled from the knotter when the latter has stopped in its outwardly-trending position. The just-mentioned oblique reach of the slot, coupled with the transverse 125 position of the knotter while the band is being laid, will of course insure that that strand which is grasped in the holder and is paid out in the recession of the binder-arm immediately after the sheaf has been ejected and 130 the knotter has reached its second or starting position, will be properly deflected and placed upon the chin of the knotter close up to the spindle in the most favorable position for ty-

ing; but it often happens that the strand brought up to be laid alongside of that first or holder strand in the rise of the binder-arm gets entangled with or pushed aside or retarded by the grain, so that it lags behind the arm, and at the moment it should enter the oblique reach of the slot is barred therefrom by the arm itself, and so is not properly presented to the knotter. There are objections 5 to the use of a cord-tucker on the arm itself to obviate this, because it weakens the arm, and, with its accessories, adds so much additional weight to the machine, and an independent cord-tucker above the breast-plate, 10 operated from the tyer-cam, although perhaps involving less weight, does involve additional mechanism and some additional weight, and although it forces the strand into position for the effective action of the knotter often 15 20 does so by pulling slack from the receptacle, leaving that part that is blocked by the binder-arm as slack in the band. Instead of adopting any of these forms I provide a bulbous breast or enlargement *i* upon the shank of the 25 binder-arm at such a point that as this arm rises it will travel close to and practically follow the slot or space along the under side of the ribs, which have for some distance a curved outline *i'*, that facilitates this action. The 30 35 breast will reach the slot sufficiently in advance of the moment when the liability of the strand to be deflected by the resistance of the grain occurs. It will so effectually close and follow this slot that the strand cannot slip past, but will be pushed before it until the arm ceases its movement, at which time the shank of the arm is at the outer extremity of the straight reach of the slot, and the strand will therefore pass readily into the oblique 40 45 reach and be deflected by the finger toward the knotter-spindle to rest upon the chin alongside the other strand and parallel therewith. The revolution of the knotter, of course, immediately succeeds this. This breast or shoulder is a mere bulbous enlargement, 50 55 easily piercing the grain, but of sufficient capacity to close the slot along the under side of the ribs, the edges of which are in contact with and depress the grain. Between these ribs the binder-arm breast cannot pass, but sweeps along them, as stated, pushing the grain as well as the cord before it. It is, therefore, to be distinguished from a tucking-finger projecting aggressively from the binder-arm.

Outside of the bearing for the tyer-spindle *K* the supporting-bracket has oblique bearings for the holder-spindle, the lower bearing *k* being near to the tyer-spindle or only at 60 such distance therefrom as to bring the holder-disk close to the tying-jaws, while the upper one *k'* throws the end of the holder-spindle out near to the periphery of the tyer-cam.

The holder consists of a circular plate or 65 disk *K'*, of proper diameter, having at or near its periphery an upturned rim or flange provided with a series of forwardly-set notches

k², giving its outline the appearance of rounded saw-teeth with their shoulders set in the direction of revolution. This disk, generally 70 called a "crown-disk," is saddled on the side nearest to the knotter by a stationary shoe *L*, the sides or flaps *l* of which pass beyond the bottom of the notches slightly, and the inner wall of which comes close to the nose of the 75 knotter-jaws when the revolution of the knotter-spindle has brought them round to a position pointing directly at the shoe. The inclined position of the holder-spindle lifts the holder-disk so as to raise the flange on the 80 side adjacent to the knotter, or, rather, to sink the flange on the opposite side, as that nearest the knotter should retain about its usual height in relation thereto, bringing the disk in a plane oblique to the line of the second 85 strand of cord stretched between the knotter and the nose of the binder-arm when the latter has encircled the gavel, with its inner side intersecting said line, and since proper construction requires that the knotter should 90 come close to the inner surface of the breast-plate and that the cord should be grasped and held sufficiently low down to enter between the knotter-jaws when they open I find it advisable to cut away the outer part of the 95 breast-plate, as at *L'*, to allow the farther side of the holder-disk to pass therethrough in order to obtain the proper inclination.

The positive grasping of the cord between the unyielding surfaces would, owing to the 100 uneven thickness of the cord and the defects known even in the best of binding-cord, result often in imperfect binding and escaping bundles. It has always, therefore, been found necessary to provide for a yielding contact 105 between the holder-disk and its shoe whatever their construction. This is accomplished herein by permitting the holder-spindle to slide in its bearings and placing between the lower bearing or thimble thereon, and a nut 110 *l'*, adjustable upon the screw-threaded portion of said spindle beneath its upper bearing, a strong coiled spring *l²*, encircling the spindle, the effect of which will be to hold the disk up against its shoe with a force determined by the adjustment of the nut, but 115 permit it to yield for varying thicknesses of cord or for lumps or defects found therein.

Heretofore the shoe has been bolted to the bracket or stock at a distance from the holder-disk and has extended thereto from this point of attachment; but in the present invention it is formed with a hub *m* to embrace the holder-spindle loosely and the stock is recessed above the disk to receive the hub. A 120 dowel-pin *m'*, passing through a portion of the stock alongside the bearing for the spindle, enters a recess *m²* in the web connecting this hub with the shoe proper, and thereby holds it against rotation with the spindle. 125 Thus in assembling the parts the hub of the shoe is slipped over the spindle and the spindle then placed in its bearings, when all parts of the holder are secured together by the 130

same means that retain the spindle from slipping out of such bearings. The flaps or depending walls of the shoe in this class of holders have also been heretofore made to terminate on the same radial line at their rear; but to permit the ready escape of the fag ends of the cord and to cause them to drop outside of the crown-disk, instead of being retained in the cup formed thereby, I cut away the inner flap in advance of the other, so that it shall release the portion of the fag end grasped by it in advance of the outer one, thus insuring that the rotation of the disk shall push the said fag end toward the outer side and that it shall be dropped from said outer side when released by the exterior flap of the holder.

To the extreme upper end of the holder-spindle, adjacent to the periphery of the tyer-cam, is pinned or fastened a pinion N, which in the present instance has twice the number of interdental spaces as are found notches in the crown-disk. At the outer edge of the cam, either upon its face or its periphery, is described a ledge n, engaging with said pinion, and which for a distance corresponding with the interval between the severing of the cord and the starting of the tyer and holder in the ensuing binding operation is so described, either upon a concentric curve, if upon the face, or upon a radius, if it is upon the periphery, as to act as a delay-ledge and hold the pinion stationary and the holder-disk consequently immovable; but at a point corresponding relatively to the initial movement of the knotter this ledge terminates and is succeeded by a short oblique or spiral ledge n', which enters the next interdental space of the pinion and causes it to turn sufficiently to carry the notch in the crown-disk, in which the cord has been laid, beneath the shoe and clamp the cord, and then the succeeding interdental space is engaged by the insetting initial end n² of the first-named flange or delay-ledge. In traveling along this oblique initial reach of the delay-ledge the pinion will be given an additional turn equal to one interdental space, the purpose of which is to carry the strands which have now been seized by the knotter and clamped between its jaws against the knife and sever them, when the holder comes to rest and is held at rest by the delay-ledge until the succeeding knotting operation commences. The knife O just mentioned is clamped to the stock in such position as to bring its cutting-edge close against the outer wall of the holder-shoe, between it and the knotter, but a little behind the point where the cord-strands are grasped by the holder at the moment when the tying-jaws receive and close upon them. The onward movement of the holder from the instant that the tying-jaws have closed and the cord-strands are securely held therein carries these end strands along the under edge of the shoe and immediately against the knife, which extends below said edge, and they are thereby severed, leaving the main strand still grasped

between the shoe and the crown-disk. The stationary knife cannot be employed to the best effect when the knotter-spindle and holder-spindle both lie in a common plane parallel with the plane of movement of the binder-arm, and therefore I place the holder-spindle in a plane farther removed from that of the binder-arm—say about half an inch—which insures certainty in the operation of the knife.

In operation, supposing the end of the cord to have been already grasped in the holder in binding the previous sheaf and the binder-arm to be still in its highest position and the knotter to have reached its position of rest with its jaws pointing transversely across the cord-slot and closing it, the binder-arm recedes, laying the cord-strand in the notch in the holder-disk, just in advance of the clamping-shoe, thence over the chin of the knotter, and then upon the deflecting-finger in the cord-slot, and finally sinking beneath the decking to its own position of rest. Grain is then fed against the strand of cord stretched from the holder to the nose of the binder-arm and across the passage-way or packing-chamber between the breast-plate and decking until sufficient has accumulated to form a sheaf, when the binder-arm rises, carrying the cord up around the gavel, through the slot in the breast-plate, which, as already stated, is closed by the enlargement or breast on the shank of the arm, so as to push the strand along before it, and finally laying it upon the deflecting-finger over the chin of the knotter alongside the first strand and in the same notch in the disk in which the first lies. The arm comes to a stop and immediately the revolution of the tyer-cam, which by means of its provisions for delay has held the holder and the knotter stationary until that moment, brings the gear-segment into engagement with the knotter-pinion and the first oblique ledge at its periphery into one of the interdental spaces of the holder-pinion and the knotter and holder begin to revolve, the revolution of the holder-disk carrying the two strands of cord beneath the shoe and laterally toward the knotter-spindle, so as to meet the knotting-jaws as they come around. At the proper moment these jaws open to receive said strands, at just which time the holder-pinion reaches the end of the oblique ledge, which has been actuating it, and the revolution of the disk momentarily ceases. Then the knotter reaches the spring-cam and its jaws are immediately closed, grasping the strands which have been received between them, and their revolution at once ceases, leaving them directed outwardly along the slot in the breast-plate, and now the second oblique ledge at the periphery of the tyer-cam, which has already engaged with the holder-pinion, begins to act thereon, turning the disk a slight distance farther, carrying the strands against the stationary knife-edge and severing them, when it also comes to a stop and is thereafter held at rest by the

delay length of its actuating-ledge. As soon as the strands are severed the ejector-fingers, by this time brought round by the revolution of the tyer-shaft, strike the sheaf and push it 5 forcibly from the machine, wrenching the knot from the tying-bill as they do this. Then the knotter-pinion is struck by the solitary tooth and turned just sufficiently to bring the bill to its starting position, with its jaws 10 across the cord-slot, and the lower delay-shoe resting on the outer delay-ledge to lock it in position until the succeeding binding operation.

I claim—

15 1. The combination, substantially as hereinbefore set forth, with the cord-knotter, of the crown-disk holder revolving upon an axis oblique to the axis of the knotter-spindle, so as to bring the inner side of the holder relatively higher than the outer side.

20 2. The combination, substantially as hereinbefore set forth, with the knotter and its spindle and with the cord-carrying arm, of the crown-disk holder mounted upon a spindle oblique to the knotter-spindle and flaring away from the tying-jaws, whereby the crown-disk is brought into a plane oblique to the line of the cord stretched between the knotter and the eye of the binder-arm when the latter 25 has finished its encircling movement with the outer side of the disk farthest from that line and the inner side elevated toward the chin of the knotter, so that the cord-strands will be laid in the notch adjacent to said knotter.

30 3. The combination, substantially as hereinbefore set forth, of the tying-bill and its spindle, the clamping-shoe, and the crown-disk mounted at the foot of a spindle, which 35 flares away from the knotter-spindle, so as to bring its head at a greater distance from the head of the knotter-spindle than is its foot from the foot of the latter, whereby the side of the crown-disk adjacent to the knotter is raised relatively to the other side.

40 4. The combination, substantially as hereinbefore set forth, of the tying-bill and its spindle, the binder-arm, the crown-disk mounted at the foot of a spindle which flares 45 away from the foot of the tyer-spindle, and a clamping-shoe embracing the rim of the crown-disk on the side adjacent to the knotter, whereby the disk-holder is brought into 50 inclination with the line of the cord between the tying-bill and the nose of the binder-arm when the latter has finished its encircling movement.

55 5. The combination, substantially as hereinbefore set forth, of the tying-bill, the crown-disk mounted upon the foot of a spindle which flares away from the foot of the knotter-spindle, the shoe embracing the rim of the crown-disk on the side adjacent to the knotter and the stationary knife bearing against the outer 60 side of said shoe, whereby the cord is severed in the continued revolution of the crown-disk after the tying operation is completed.

6. The combination, substantially as hereinbefore set forth, with the tying-bill, of the crown-disk mounted upon a spindle that is 70 set in a plane farther from the plane of movement of the binder-arm than is the knotter-spindle, the shoe embracing the rim of the crown-disk on the side adjacent to the knotter, and the stationary knife bearing against 75 the outer side of said shoe between it and the knotter.

7. The combination, substantially as hereinbefore set forth, of the tying-bill, the crown-disk mounted upon the foot of a spindle that 80 flares away from the foot of the knotter-spindle and is set in a plane farther from the plane of movement of the binder-arm than is the knotter-spindle, the shoe saddling the rim of said disk on the side adjacent to the knotter, 85 and the stationary knife between the holder and the knotter.

8. The combination, substantially as hereinbefore set forth, of the crown-disk, its spindle, the socketed bearing adjacent to said 90 crown-disk, the shoe having a hub which sits into said socket and receives the spindle, and means for preventing the rotation of said shoe, whereby the shoe is secured by the disk and its spindle.

9. The combination, substantially as hereinbefore set forth, of the crown-disk, its spindle, the socketed bearing for said spindle adjacent to the crown-disk, the shoe having a hub fitting into said socket and receiving the 95 spindle, and a dowel-pin passing through the hub and into a seat in the web, connecting the shoe and the hub.

10. The combination, substantially as hereinbefore set forth, of the crown-disk, its spindle, the socketed bearing for said spindle adjacent to the crown-disk, the shoe having a hub fitting in the socket in said bearing and receiving the spindle of the crown-disk, the coiled spring encircling the spindle above 110 said bearing, and the adjusting-nut turning upon a screw-thread cut in said spindle beyond the spring, whereby the crown-disk, the spindle, and the shoe are all retained in position by said spring and nut.

11. The combination, substantially as hereinbefore set forth, with a crown-disk holder, of a shoe saddling its notched rim and having the inner flap cut away in advance of the outer flap, whereby the fag ends of cord will 120 be first released by the inner flap that they may be thrown to the exterior of the holder by the further clamping action of the outer flap.

12. The combination, substantially as hereinbefore set forth, of the tying-bill, the cord-holder, the slotted breast-plate, the ribs at each side of said slot beneath the breast-plate, formed with a curve, as set forth, practically concentric with the axis of the binder-arm, and the shoulder on the shank or stock 130 of said binder-arm, arranged to sweep the slot along and in close proximity to said curved portion to push the second strand of the band before it.

13. The combination, substantially as hereinbefore set forth, with the knotter, crown-disk holder, and the holder-spindle, of a pinion fixed to the head of said spindle, and the 5 cam-flange at the periphery of the tyer-cam, having the concentric-reach n , whereby the pinion is held against revolution, and the spiral or outsetting reaches $n' n^2$, whereby said pinion is given two successive movements to 10 operate the disk.

14. The combination, substantially as hereinbefore set forth, with the tying-bill, its pinion, the intermeshing teeth and delay-ledges upon the tyer-cam, whereby said bill is 15 revolved to a position trending outwardly to form the knot and is then stopped and finally carried forward to its starting position and stopped, of the crown-disk holder, its shoe, the holder-spindle flaring outwardly from the

foot of the knotter-spindle, the pinion upon 20 the head of said holder-spindle, having double the number of interdental spaces that there are notches in the crown-disk, and the flange upon the periphery of the tyer-cam, engaging with the interdental spaces of said spindle 25 and having a long delay-reach to hold said pinion and disk stationary while the knotter is at rest, an oblique reach to revolve said pinion one notch to clamp the cord at the time the knotter begins to revolve, and a sec- 30 ond oblique reach to revolve said pinion another notch after the tying-bill has laid the knot to carry the strands against the stationary knife and sever them.

E. M. KELLOGG.
